(21) Appl. No.: **29/261,426**

Assistant Examiner—Cynthia M. Chin

(22) Filed: **Jun. 15, 2006**

(57) **CLAIM**

(51) **LOC (8) Cl.** 21-01

I claim the ornamental design for a indoor playhouse for children, as shown and described.

(52) **U.S. Cl.** **D21/506**

DESCRIPTION

(58) **Field of Classification Search** D21/483, D21/506-511, 811, 814, 826, 827; 446/476,

A visually appealing indoor playhouse that is attached to a wall of a home or classroom to enable the creation of a square enclosed fort in the corner of a room.

446/478, 110, 111; 52/64, 70-73

FIG. 1 is a front elevational view of the door portion of the indoor playhouse for children showing my new design, shown separately for clarity of illustration;

See application file for complete search history.

FIG. 2 is a back elevational view thereof;

(56) **References Cited**

FIG. 3 is a front elevational view of the window portion of the indoor playhouse for children, shown separately for clarity of illustration;
